UNITED STATES PATENT OFFICE.

WILLIAM BAIRD MARBLE, OF LOS ANGELES, CALIFORNIA, ASSIGNOR TO SOUTHERN GLASS COMPANY, A CORPORATION OF CALIFORNIA.

DESIGN FOR A BOTTLE.

Application filed June 12, 1922. Serial No. 2,630. Term of patent 14 years.

To all whom it may concern:

Be it known that I, WILLIAM BAIRD MARBLE, a citizen of the United States, residing at Los Angeles, in the county of Los Angeles and State of California, have invented a new, original, and ornamental Design for Bottles, of which the following is a specification, reference being had therein to the accompanying drawing.

The drawing is an elevation of a bottle showing my new design.

I claim:—

The ornamental design for a bottle, as shown.

In testimony whereof I affix my signature.

WILLIAM BAIRD MARBLE.
